(57) **CLAIM**

The ornamental design for a media switcher as shown and described.

DESCRIPTION

FIG. 1 is a top view of a media switcher showing our new design;

FIG. 2 is a front view thereof;

FIG. 3 is a rear view thereof;

FIG. 4 is a left side view thereof;

FIG. 5 is a right side view thereof;

FIG. 6 is a bottom view thereof;

FIG. 7 is a front perspective view; and,

FIG. 8 is a rear perspective view thereof.

The broken lines shown in the drawings depict portions of the media switcher that form no part of the claimed design.

1 Claim, 8 Drawing Sheets
